UNITED STATES PATENT OFFICE.

JACOB H. BROWN AND JOHN H. BROWN, OF MARSEILLES, ILLINOIS.

RAIN-COAT.

1,055,703.

Specification of Letters Patent. Patented Mar. 11, 1913.

Application filed January 24, 1912. Serial No. 673,174.

To all whom it may concern:

Be it known that we, JACOB H. BROWN and JOHN H. BROWN, citizens of the United States, and residents of the city of Mar- 5 seilles, county of Lasalle, and State of Illinois, have invented certain new and useful Improvements in Rain-Coats, of which the following is a specification.

Our invention relates to rain coats and 10 more specifically to a coat of this character of inexpensive construction, adapted to be transported in a hand-bag or other package used in traveling for employment in case of emergency to protect the garments of the 15 wearer.

The object of our invention is the production of a rain coat, as mentioned, which will be of improved construction and efficient in use.

20 Other objects will appear hereinafter.

Our invention consists in the combinations and arrangements of parts hereinafter described and claimed.

Our invention will be best understood by 25 reference to the accompanying drawings forming a part of this specification, and in which—

Figure 1 is a front elevation of a rain coat embodying our invention, Fig. 2 is a 30 fragmentary detail rear view of the upper end portion of the coat, Fig. 3 is an enlarged detail section taken on line $\alpha\alpha$ of Fig. 1, Fig. 4 is a detail section taken on line $\gamma\gamma$ of Fig. 1, and Fig. 5 is a plan view 35 of the blank from which the coat is formed.

The preferred form of construction, as 40 illustrated in the drawings, comprises a blank which is formed of any suitable waterproof material, such as oiled paper or the like. Said blank comprises the substantially rectangular body portion 1 from which the body of the coat is formed, as hereinafter described. Projecting centrally 45 from the longitudinal edges of the body 1 are sleeve-forming portions 2. In forming the coat the blank is bent upon the line A so that the longitudinal edges of the sleeve-forming portions will be brought in registration as well as the longitudinal edges of 50 the respective ends of the body 1, said edges being secured together at the dotted lines B preferably by cementing or gluing, the resulting coat presenting an appearance as shown in Fig. 1. The front side of the coat 55 or the lower end portion of the blank is open or slitted, the edges 3 and 4 being bent upon

themselves, as shown in Fig. 3, for reinforcement. Secured to the edge 3 are buttons 5 which are adapted to engage button-holes 6 formed in the edge 4, tabs 7 being formed at 60 said edge 4 in order to additionally reinforce the same.

At the upper extremities of the edges 3 and 4 are formed lapels 8, one of said lapels being provided with a button 9 and the other 65 with a button-hole 10 for securing said lapels in overlapping position. A tab 11 is preferably formed at the button-hole 10 in order to reinforce the same.

At the lapels, the body 1 is provided 70 with a circular recess 12 which forms a neck opening. Secured to the body 1 at the neck opening is a collar piece 13, the extremities of said collar piece being secured to projections 14 provided at the upper extremities 75 of the lapels 8, as clearly shown in Fig. 5.

In order to reinforce the garment under the arms or at the juncture of the undersides of the sleeves with the body of the garment, reinforcements 15 may be provided 80 at this point, said reinforcements in addition to serve as reinforcements, serving also as a means of drawing the sleeves downwardly to proper or operative position.

85 A coat of the construction set forth may be manufactured at an extremely low cost and will be adapted to effectually serve to protect the garments of the user in rainy or inclement weather. The coat may be folded 90 into small compass for convenience in transportation so as to be ready for use at any time.

While we have illustrated and described 95 the preferred form of construction for carrying our invention into effect, this is capable of variation and modification without departing from the spirit of the invention. We, therefore, do not wish to be limited to the exact details of construction set forth, 100 but desire to avail ourselves of such variations and modifications as come within the scope of the appended claims.

Having described our invention, what 105 we claim as new and desire to secure by Letters Patent, is:

1. A coat comprising a body and sleeves made of an integral piece of water-proofed paper, such body being provided with an open front and having the edges along said 110 open front turned upon themselves and secured thereto to form reinforced edges and

- lapels; and ears formed integrally with one of such edges and turned upon such edge and secured thereto, substantially as described.
- 5 2. A coat comprising a body and sleeves made of an integral piece of water-proofed paper, such body being provided with an open front and having the edges along said open front turned upon themselves and secured thereto to form reinforced edges and lapels; ears formed integrally with one of such edges and turned upon such edge and

secured thereto; and reinforcements formed integrally with and at the juncture of the sleeves and body, substantially as described. 15

In testimony whereof we have signed our names to this specification in the presence of two subscribing witnesses.

JACOB H. BROWN.
JOHN H. BROWN.
